(57) **CLAIM**

The ornamental design for a connector for a faucet mounted water filter, as shown and described.

DESCRIPTION

FIG. 1 is a perspective view of a connector for a faucet mounted water filter illustrating my new design;

FIG. 2 is a top planar view of the design of FIG. 1; and,

FIG. 3 is a bottom planar view of the design of FIG. 1.

The broken lines form no part of the claimed design.
